United States Patent Office

Des. 181,441
Patented Nov. 12, 1957

181,441

PATIO AWNING

Adrien A. Poirier, San Diego, Calif., assignor to Chemi-
glas, Inc., San Diego, Calif., a corporation of Cali-
fornia

Application October 1, 1956, Serial No. 43,167

Term of patent 14 years

(Cl. D21—6)

*Fig. 2**Fig. 3*Fig. 1 is a front perspective view of a patio awning showing my new design;

Fig. 2 is a view of the underneath side thereof taken on line 2—2 of Fig. 3; and

Fig. 3 is a side elevational view thereof.

The dotted line illustration of parts of a roof are for illustrative purposes only.

I claim:

The ornamental design for a patio awning, as shown and described.
